Primary Examiner — Holly Baynham(74) *Attorney, Agent, or Firm* — Michael Best & Friedrich LLP(57) **CLAIM**

The ornamental design for a vertical bifold cell phone wallet, as shown and described.

DESCRIPTION

FIG. 1 is a perspective view of a vertical bifold cell phone wallet with an exterior framed pocket and interior slot pockets according to another embodiment showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the vertical bifold cell phone wallet with an exterior framed pocket and interior slot pockets in an open condition;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The present application is directed to the design illustrated in the drawings. The broken lines showing portions of the cell phone wallet are for purposes of illustrating environment only and forms no part of the claimed design.
